ATTORNEY

Leach, Taylor,
WITNESS:

UNITED STATES PATENT OFFICE

WILBUR E. PARKER, OF EVERETT, MASSACHUSETTS

ROLLING WINDOW SCREEN FOR AUTOMOBILES

Application filed June 28, 1929. Serial No. 374,454.

The object of this invention is to provide a screen for the vertical slidable window of a motor car and particular means for connecting the wire netting with the upper edge of the glass plate.

A further object is to provide a screen automatically adjustable to any position in which the window may be placed, and a device which may be promptly attached or detached with reference to the glass and when attached will maintain firm connection therewith without danger of fracture of the edge of the window or of becoming accidentally displaced therefrom.

15 A further object is to prevent injury to the glass in the event of pressure on the attaching means resulting from moderate impact due to a slight blow from any cause.

With the foregoing and other objects in view, the invention consists in the novel construction and arrangement of elements disclosed, it being understood that modifications may be made within the scope of the claims without departing from the spirit of the invention.

In the drawings forming part of this application:—

Figure 1 is a view in vertical section thru a window which may be considered of usual type and similar to that used in motor cars in which the glass plate is slidable vertically in the frame.

Figure 2 is a fragmentary view in elevation.

35 Figure 3 is a fragmentary view in vertical section, and shows a cam clamping device.

Figure 4 shows the structure of Figure 3 in elevation, and constitutes a fragmentary view.

40 Figure 5 is a detail in section through the vertical guide appearing in Figure 3 and elsewhere.

The glass plate is designated 10, and is assumed to be slidable within the frame work 45 11, and beyond or outside of the plane of movement of the glass, I mount a roller 12 on which a wire netting or fabric 13 is to be wound and unwound,—the roller preferably being of the spring controlled type.

50 In order to clamp the netting to the upper

edge of the glass, I provide particular securing means, and the netting is secured at 13' to a plate or strip 14, this element last named being adapted to carry an element 15 of rubber or the like having recesses or cups 55 16 therein constituting vacuum cups.

A complementary clamping element includes the plate portion 18 and the socket portion 19 receiving a screw or other securing device 20.

Element 18 carries a rubber or other pliable strip 18', this element also being provided with cups or recesses, so that a firm grip may be secured on the edge of the glass plate 10 without danger of fracture either under 65 normal circumstances or when there may be moderate angular movement of the clamping plates or strips.

Roller 12 may be mounted below the upper angular plate 21, and a strip 22 of rubber bearing on the rolled screen will afford protection from the weather. Guides 23 receive the edges of the mesh and close any space at the sides.

In Figures 3 and 4 I have illustrated a threaded device 20', adapted to be controlled by a cam lever 25, the operation of the other elements of the combination being similar to that already described.

What is claimed is:—

1. In a device of the class described, means for connecting a screen with a window, these means including a pair of clamping elements, one of which is offset laterally toward the other and is provided with a socket portion, an adjustable device entering the socket and passing thru said other clamping element, the latter being slotted for an edge portion of the screen, a cam mounted on the adjustable device and positioned to bear on the clamping element opposite that having the socket, and a plurality of devices on the approaching face portions of the clamping elements and formed with cups from which air is forced under pressure of the cam. 85 90 95

2. Means for connecting rigid and flexible closure elements for the opening of a door frame, said means comprising parallel clamping elements, movable together in parallel planes, and each providing on reverse 100

sides thereof rigid and pliable surfaces, the pliable surfaces approaching each other for cushioned engagement with a glass plate for a door, one of the clamping elements being 5 grooved longitudinally for the flexible closure element, the other clamping element including socketed portions, and means for adjustably connecting the socketed portions with the clamping element having the groove.

10 In testimony whereof I affix my signature.
WILBUR E. PARKER.
